UNITED STATES PATENT OFFICE

JOHN WRIGHT WARREN, OF KNOXVILLE, TENNESSEE

BUILDING UNIT

Application filed May 23, 1930. Serial No. 455,089.

My invention relates to tile building units or blocks, and more particularly to a new and useful type of coping tile adapted to be used in the upper course of a masonry structure 5 or in the drain or shed course of a wall.

A primary object of the invention is to provide a unit having at its longitudinal ends, or elsewhere as required, integral joint portions adapted to interlock with the opposite 10 joint of an adjoining unit, and to be closely united thereto without the use of interposed mortar or the like.

Another object is to provide a unit which when interfitted with a similar unit without 15 the use of mortar or the like, will provide a rainproof joint, effectually protecting the material in the wall beneath from disintegration by rain water.

A further object is to provide units of the 20 character indicated which will, when placed in operative position, assimilate all normal contraction and expansion from heat and cold.

A further object is to provide a unit which 25 may conveniently be made from natural stone, concrete, ordinary clay, or similar plastic material, and which will be light, economical and efficient.

While the unit which forms the subject of 30 this application for Letters Patent is particularly useful as an element of a wall coping, it is to be understood that the invention relates especially to the interfitting ends of a tile or building block, the body portion of which 35 may be variously formed and shaped for a variety of purposes and uses, including disposition in the interior courses of a wall, pavement, floor, etc. Consequently the invention which is described and claimed herein 40 is not to be considered as limited to embodiment in tiles or blocks adapted to be used only in the construction of copings.

Other and further objects of my present 45 invention will be apparent from a consideration of the accompanying drawings and the following specification, in which the details of the invention in one form of embodiment are pointed out.

50 In the accompanying drawings which

form part of this application for Letters Patent,

Figure 1 is a top plan view of a unit constructed according to the principles of the present invention;

55

Fig. 2 is a bottom plan view of the unit shown in Fig. 1;

Fig. 3 is an end elevation of the unit showing one of the interlocking ends;

Fig. 4 is an end elevational view of the 60 opposite end of the unit shown in Fig. 3;

Fig. 5 is a perspective view of the upper portion of an end wall showing a pair of units in operative position thereon; and

Fig. 6 is a perspective view with one end 65 in section of the upper portion of a wall showing a pair of units formed in accordance with the principles of the present invention, in interfitted relation.

Referring now to the drawings, and first to Figure 1, the reference numeral 1 indicates the body portion of a unit, which is conveniently formed of any suitable material, such for example as natural stone, concrete, clay, terra cotta, or the like. For convenience in handling, and economy of material, the underside of the body portion is preferably recessed, as shown at 2.

The interfitting drain portions which constitute the essence of the present invention 80 are formed on the longitudinal ends of the body 1, and are preferably made integral therewith. The normal unit made according to the principles of this invention, i. e., one which is to be received between a pair of similar units, as shown in Fig. 6, is provided with a male end 3, and an opposite female end 4.

The male end consists in an extension having a lower surface flush with the under surface of the body 1, and a pair of inclined upper surfaces 5 and 6, which meet in an apex 7, substantially below the upper surface of the body 1.

The inclined upper surfaces 5 and 6 of the male end are each provided with a relatively shallow channel 8 and 9 respectively which conform closely in inclination and length to the surfaces 5 and 6.

100

The female portion at the opposite end of the body comprises a recess 10, bounded by surfaces 11 and 12 of the body, which meet in a vertex 13 and conform in their angular inclination with the surfaces 5 and 6 of the male end 3. Similarly, the depth of the recess 10 is equal to the thickness of the extension constituting the male end.

At the female end of the body 1, channels 14 and 15 are provided, each in the rear respectively of the surfaces 11 and 12, in such a way that channels 14 and 15 of the female end of one unit are adapted respectively to receive surfaces 5 and 6 of the male end of another similar unit, as best shown in Fig. 5.

The under surface of the body 1 is provided, near the outer surfaces thereof, with a pair of longitudinal grooves 16, for a purpose hereinafter explained.

The male end 3 is provided, in the under surface thereof, with an indentation 17 to facilitate handling of the unit. A smaller indentation 18 is also provided in the under surface of the portion 3 immediately adjacent to the lower part of the inclined surface 6. The purpose of this indentation will be hereinafter explained.

In applying the units to operative position, upon the top surface of a wall such as shown in Figures 5 and 6, a thin grouting of mortar is first placed along the edges of the wall. The units are then set upon this grouting with their end portions interfitted as shown in Figures 5 and 6, in a manner which will be obvious. I prefer in practice to make the units of a width slightly greater than that of the wall with which it is to be used, so that the sides of the units will overhang the wall slightly, as shown in Figures 5 and 6. The endmost unit of the wall is conveniently provided with one plane end portion 19, as shown in Fig. 5.

It is to be remembered that in interfitting a pair of units no grouting is used in the joint. When rain water or the like falls upon the upper face of a pair of interfitted units, some quantity thereof will penetrate into the joint space until it reaches the channel 8 or 9 of the male portion 3. Since the floors of the channels are below the level of the end face of the extension constituting male end 3, the water will be prevented by the surfaces 5 and 6 from escaping from the channels 8 and 9 into the body of the wall, and will necessarily find its way by gravity down along the channels 8 and 9 to issue from the end thereof.

The base or floor of each of the channels 8 and 9 is spaced sufficiently from the adjacent surface 14 and 15, respectively, of the cooperating recessed or female end to prevent capillary attraction between these surfaces. Water penetrating to this portion of the joint is therefore carried down the inclined channel by force of gravity alone and

delivered out of the unit at one or the other side face thereof.

The channels 8 and 9 extend toward the sides of the tile body and terminate beyond the vertical planes of the wall which the tiles are intended to cover. In the embodiment of the invention which I have illustrated in the accompanying drawings, the channel 8 terminates in the rear side wall of the body 1 and the channel 9 in the base thereof, but it is to be understood that the precise location of the ends of these channels is immaterial to my invention, although I prefer that the unit be so designed that water in the channels will be discharged at points beyond the planes of the wall on which the units are positioned, and beyond the groove 16 or indentation 18 in the body of the tile. The effect of this construction is to cause water in the channels to be positively shed at the end of the channels, and dropped out of contact with the wall, the groove 16 and indentation 18 preventing drops held against the under surface of the unit by capillary attraction from moving inwardly to wet the wall.

Each unit is preferably provided with one male and one female end, but it will be appreciated that the invention may be embodied in different units formed respectively with two male ends and two female ends. In the latter embodiment of the invention the wall or coping course is built up of alternate double male units and double female units, the interfitting drain portions of adjacent units cooperating exactly as in the case of the preferred form of the invention where each unit carries a male and a female end.

I have illustrated and described my present invention in only one form of embodiment merely by way of exemplification. It is to be understood that the invention is capable of embodiment in other and different modifications, but all such modifications, to the extent that they embody the principles of the invention, are to be deemed within the scope and purview of the appended claims.

What I claim and desire to secure by Letters Patent is:

1. A building unit comprising a body portion, an extension at one end thereof of smaller area than the end of the body portion adapted to fit in a complementary recess in another unit, having a pair of downwardly inclined upper surfaces and a channel in each of the upper surfaces of the extension.

2. A building unit comprising a body portion having an extension at one end thereof of smaller area than the end of the body portion and having a pair of downwardly inclined upper surfaces, and a recess in the opposite end of the body portion complementary in shape with the extension.

3. A building unit comprising a body portion having an extension at one end thereof

of smaller area than the end of the body portion provided with a pair of downwardly inclined upper surfaces and a channel in each of said surfaces, said body being provided at its opposite end with a recess conforming substantially to the shape of the projection.

4. A building unit comprising a body portion having an extension at one end thereof of smaller area than the end of the body portion provided with a pair of downwardly inclined upper surfaces and a channel in each of said surfaces, said body being provided at its opposite end with a recess conforming substantially to the shape of the extension and having a drip indentation in its under surface between the end of the channel and the longitudinal axis of the body.

5. A building unit comprising a body portion, an extension at one end thereof adapted to fit into a complementary recess in another unit, said extension having a downwardly inclined upper surface provided with a channel drain for conducting water to the side of the unit, the base of the channel drain being spaced a substantial distance from the adjacent surface of the complementary recess.

6. A building unit comprising a body portion, an extension at one end thereof adapted to fit into a complementary recess in another unit, said extension having a downwardly inclined upper surface provided with a channel drain for conducting water to the side of the unit, a portion of the channel drain being spaced sufficiently from the adjacent surface of the recessed unit to prevent capillary attraction on water between said surfaces.

In testimony whereof I affix my signature.

JOHN WRIGHT WARREN.
